MUFFLER FOR GAS-ENGINES.

1,084,290.

Specification of Letters Patent.

Patented Jan. 13, 1914.

Application filed August 21, 1912. Serial No. 716,113.

To all whom it may concern:

Be it known that I, LOUIS F. PELLETIER, a citizen of the United States, residing in New York city, in the county of New York and State of New York, have invented certain new and useful Improvements in Mufflers for Gas-Engines, of which the following is a specification.

This invention has for its object to provide an improved form of muffler device, or silencer, in which the hot gases are first caused to travel practically throughout the length of its outer wall to be thereby reduced in temperature, and consequently, compression; the gases being then caused to return to the forward or inlet part of the muffler and pass through a large number of small openings into an inner chamber, through which they find outlet at the other end of the device.

Reduction in the temperature and tension of the exhaust gas is due almost altogether to their deflection into contact with the cold outer wall of the muffler, and the tortuous passage and foraminous plate through which they subsequently pass reduce and nullify the eddies and pulsations in said gas, and materially aid in silencing the exhaust, but obviously necessitating a higher back pressure in the engine. In many places a little noise is objectionable only to the users of the engine; and I therefore provide a valve-controlled bypass to the atmosphere in the muffler anterior to such obstructions through which the cooled exhaust can be discharged at the will of the operator, with some little noise, but with less back pressure and am thus enabled to have a silent engine, or a nearly silent but more efficient engine, according to its place of use.

In the accompanying drawings, illustrating one embodiment of my invention, Figure 1 is a longitudinal section; Fig. 2 is a section on the line 2-2 of Fig. 1; and Fig. 3 is a section on the line 3-3 of Fig. 1.

The device is shown as comprising a casing 5, which because it is in contact with the atmosphere, is my most effective cooling surface and is shown as cylindrical and having an inlet pipe 6 at the opening in the rear end 7. At the other end 8 an exit pipe 9 is provided, and also a by-pass or outlet valve 10 to control a by-pass 11 to the at-

mosphere in this forward end which opening is adjacent one side. 55

Inside the casing at the middle portion, is arranged a cylinder (using that term broadly) 12 that is slightly smaller than the casing and preferably a slightly tapered truncated cone, with its base end 13 anterior 60 and open, and the small end 14 connected with a cone 15 located axially with and having its apex a short distance from the inlet pipe 6 at this end. This organization forms a variably converging passage 16 between the casing 5 and the compound cone 15 and 12, the posterior portion 16^a of which, about the cone 15, converges rapidly, while its outer portion 16, converges much less rapidly and will cause the gases entering 70 through the pipe 6 to be deflected around the cone 15, and to form large whirls or rings about its point, and in their traverse of the quickly converging passage 16^a, to roll upon said cone and the enveloping surface 75 of the casing 5, to part with their heat to the latter (which is cooled by contact with the atmosphere); as they approach the less rapidly converging portion 16^a of the passage 16, about the truncated cone 12, the 80 exhaust gases move in larger whirls, with less actual velocity; and while traversing said passage the whirls will gradually be nullified and the motion of the gases will be converted into axial currents along and 85 in contact with the outer wall of the casing to be cooled by the atmosphere engaging the casing before they reach the rear portion 17 of the casing.

The combination of the inlet pipe 6, head 90 7, casing 5, and compound cone 15-12, constitute an efficient cooler and condenser for the exhaust gases and silencer for use where a slightly noisy exhaust would not be objectionable; and were it not for the fact that 95 in many localities the exhaust must be rendered as nearly as possible noiseless, I should cut off the casing 5 adjacent to the base of the truncated cone 12 and dispense with all other members; and by so doing would admit the atmosphere to the interior of the compound cone 15-12 and increase the gas-cooling efficiency of the apparatus. But the complete organization illustrated will render the exhaust almost entirely noiseless. I 100 105 therefore provide an axially, inwardly ex-

tending, preferably conical tube 18 communicating with the pipe 9, this tube being shown as expanding inwardly, and provided with openings 20 through its inward portion to admit the gas, it being shown as having its inward end 19 secured to the cone 15. The gases issuing as an annular current from the passage 16, form whirls in the annular chamber 17, traverse it, strike its head 8 and rebound; and since they cannot find direct exit through the pipe 9 form whirls and a reverse current around the tube 18, pass through a large number of small openings 20 in the inward end portion of the cone 18. After passing through these small openings 20 the gas will pass through the tube 18 and thence through the outlet pipe 9. By this means it will be seen that the gas on entering through the inlet will be deflected in all directions by the cone, and will first flow between the cone and the cylinder and in contact with the inner wall of the casing until it reaches the annular chamber 17. From thence the gas must pass through the tapering annular chamber 21 and in numerous small streams through the holes 20 to reach the interior of the tube 18 whose convergence will effectively convert said small streams of gases into a smooth and continuous current and practically noiseless final exhaust through the discharge pipe 9. But where the resulting increase of noise is not objectionable the by-pass valve 10 can be manipulated to open the by-pass 11 and put the chamber 17 in direct communication with the atmosphere so that gases can be directly discharged therefrom, thus preventing such back pressure as might be caused by forcing the gas through the opening 20 and the tube 18.

The compound cone 15—12 can be secured in position by lugs 22 connecting it with the casing. The tube 18 is secured to the end 8 of the casing and cone 15, whereby it is suitably supported.

The compound cone may be more accurately described as a conoidal deflector 15—12 of graduated obliquity adapted, together with the casing 5, to form an annular converging passage 16, the convergence of which is suitably graduated. Obviously, the efficiency of the muffler could be slightly increased, with increased cost, by distributing the graduation among successive zones 50 of the conical deflecting surface; as for example, by generating said surface by the revolution, about the axis, of a suitably curved line.

Having thus described my invention, I claim:

1. An exhaust muffler for gas engines comprising an inlet, a casing of uniform sectional area and a conoidal deflector all on a common axis, the apex of the deflector adjacent to the inlet, a quickly-divergent conical

surface adjacent to the apex, and a less divergent surface adjacent to the base of the deflector.

2. An exhaust muffler for gas engines comprising an inlet, a casing of uniform sectional area and a conoidal deflector all on a common axis, the apex of the deflector adjacent to the inlet, and on said deflector a surface of graduated obliquity, graduated from maximum obliquity adjacent to the inlet to minimum obliquity adjacent to its base.

3. An exhaust muffler for gas engines comprising an inlet, a casing of uniform sectional area and a conoidal deflector all in a common axis, said deflector comprising a cone with its apex adjacent to the inlet, and a truncated cone joined to and diverging from said cone but at a lesser angle than the divergence thereof.

4. An exhaust muffler for gas engines comprising an inlet, a casing of uniform sectional area and a conoidal deflector all in a common axis, said deflector having its apex adjacent to said inlet and its conoidal surface generated by the revolution about its axis of a line generally convex and, reckoned from the apex, gradually approaching said casing.

5. An exhaust muffler for gas engines comprising a casing of uniform sectional area, heads closing the ends thereof, and, axially therewith, an inlet in one and a discharge through the other of said heads, a conoidal deflector of graduated obliquity relatively to and decreasing as it approaches said casing, and a silencing tube joined to the discharge head about said discharge and extending into the deflector.

6. An exhaust muffler for gas engines comprising a casing, heads closing the ends thereof, and, axially therewith, an inlet in one and a discharge through the other of said heads, a conoidal deflector of graduated obliquity relatively to and decreasing as it approaches said casing, a truncated cone joined to the discharge head about said discharge extending into the deflector, and a valve controlled by-pass between the interior of said casing and the atmosphere.

7. An exhaust muffler for gas engines comprising a casing, heads closing the ends thereof, and, axially therewith, an inlet in one and a discharge through the other of said heads, a conoidal deflector of graduated obliquity relatively to and decreasing as it approaches said casing, a truncated cone joined to the discharge head about said discharge extending into the deflector, and a valve controlled by-pass in the discharge-head.

8. An exhaust muffler for gas engines comprising an inlet, a casing and a conoidal deflector all on a common axis, the apex of the deflector adjacent to the inlet, a quickly di-

vergent conical surface adjacent to the apex and a less divergent surface adjacent to the base of the deflector and forming with the casing a passage converging toward its discharge.

5 9. An exhaust muffler for gas-engines comprising an inlet, a casing and a conoidal deflector all on a common axis, the apex of the deflector adjacent to the inlet, a quickly di-

vergent conical surface adjacent to the apex and the less divergent surface adjacent to the base of the deflector and forming with the casing a passage converging gradually toward its discharge.
